RAILWAY DRAFT RIGGING

John F. O'Conner, Chicago, Ill., assignor to W. H. Miner, Inc., Chicago, Ill., a Corporation of Delaware

Application February 15, 1929. Serial No. 340,267

2 Claims. (Cl. 213—7.)

This invention relates to improvements in railway draft riggings.

One object of the invention is to provide a draft rigging for railway cars including draft sills, coupler means, shock absorbing mechanism between the sills actuated by the coupler in buff, yoke means to which the coupler is keyed for actuating the shock absorbing mechanism in draft, outer stop means for the shock absorbing mechanism including a stop key working in slots in the draft sills, wherein relatively longer travel of the coupler is provided for in buff than in draft to take care of the heavier buffing shocks.

Another object of the invention is to provide a railway draft rigging of the character indicated in the preceding paragraph, wherein the shock absorbing mechanism has relatively light initial action followed by heavier action during the last part of the stroke in buff and affords relatively light action in draft.

A further object of the invention is to provide a railway draft rigging including spaced draft sills, coupler means, two separate shock absorbing mechanisms disposed between the sills, a yoke connecting the coupler with one of the shock absorbing mechanisms to actuate the same in draft, an outer stop key cooperating with the last named shock absorbing mechanism, the coupler actuating both of the shock absorbing mechanisms in buff to provide a relatively longer stroke of the coupler in buff than in draft and also afford much heavier resistance.

A still further object of the invention is to provide a shock absorbing mechanism for railway draft riggings having relatively longer travel in buff than in draft and including two shock absorbing means actuated in series in buff and only one of which is actuated in draft, the latter being disposed within a yoke acting means connected to the shank of the usual coupler by the ordinary coupler key, wherein the yoke means also houses the outer main follower of the shock absorbing means and has means thereon for guiding the coupler shank and wherein the outward movement of the main follower is limited by a stop key cooperating with the draft sills, the parts being so proportioned that the coupler key and stop key are adapted to cooperate with the usual standard key openings provided therefor in draft sills.

Other and further objects of the invention will more clearly appear from the description and claims hereinafter following.

In the drawing forming a part of this specification, Figure 1 is a longitudinal vertical sectional view through the underframe structure at one end of a car, illustrating my improvements in connection therewith. Figure 2 is a horizontal longitudinal sectional view, corresponding substantially to the line 2—2 of Fig-

ure 1. Figures 3 and 4 are transverse vertical sectional views, corresponding respectively to the lines 3—3 and 4—4 of Figure 1.

In said drawing, 10—10 indicate the usual spaced center or draft sills of a railway car underframe; the sills are of the channel type and have cheek plates 11—11 secured to the outer end portions of the same, the cheek plates being each provided with a pair of key receiving openings 12 and 112. The openings 12 of the cheek plates are in alignment and are adapted to accommodate the usual coupler key. The key openings 112 are also in transverse alignment and are adapted to receive the usual stop key which cooperates with the outer follower of the shock absorbing mechanism. The body bolster at one end of the car is designated by 13 and has a combined filler and stop casting 14 mounted thereon between the sills 10. The stop casting 14, as shown, is provided with a front stop face 15 and forwardly extending spaced stop arms 16—16 which have abutment or stop faces at the front ends thereof for a purpose hereinafter described. The end sill of the car is designated by 17 and is provided with an opening 18. The center sills 10 extend forwardly to the end sill and are secured thereto and the cheek plates 11 are provided with lateral outwardly extending flanges 19—19 which are secured to the vertical web of the end sill. The bottom side of the opening 18 in the end sill is closed by a carry iron member 20 which is bolted to the bottom of the end sill and has a wear plate 21 seated thereon.

In carrying out my invention, I employ the usual standard coupler which is indicated by 22 and is provided with the usual transverse key receiving opening 23 in the shank thereof. The coupler head is only partly shown in the drawings so as to accommodate the view to the size of the sheet. The coupler shank has a lost motion connection with yoke means 24 in the form of a rectangular sleeve member having spaced, longitudinally disposed side walls 25—25, a relatively short top wall 26, and a transverse rear end wall 27. The side walls 25 have the inner surfaces at the forward end of the yoke means diverging laterally outwardly so as to permit the necessary amount of pivotal lateral swinging movement of the coupler when cars are operated on curved track. The coupler key, which is indicated by 28, extends through aligned openings 29—29 in the side walls 25 and has the opposite ends thereof working in the openings 12 of the draft sills. As shown, the key 28 is headed at one end and is provided with detachable securing means at the opposite end. Inwardly of the openings 29, the side walls 25 are thickened, as shown, thereby providing transverse shoulders 30—30. Intermediate the ends of the yoke means, the top wall 26 is provided with a thickened portion 31

- which, together with a transverse relatively thick bottom web 32 connecting the side walls 25, defines a guideway for a pressure transmitting block, hereinafter more fully described. The top wall has the inner end portion thereof terminating in alignment with the shoulders 30, thereby providing a relatively large opening between the inner end of the top wall and the end wall 27 of the yoke means.
- At the forward end, the yoke means is provided with a horizontal web 33 spaced from the top wall and connected thereto by a vertical wall section 34, the web extending inwardly from said vertical wall section. At the forward end, the yoke means is also provided with a bottom wall 35 extending forwardly from the transverse web 32, the central portion of said wall being cut away to provide an opening to render the interior of the yoke accessible. Immediately above the wall 35, the yoke means is provided with a relatively narrow transverse web 36 connecting the side walls and disposed parallel to the top web 33. The web 36 is connected to the bottom wall 35 by a vertical end wall section 37. As most clearly illustrated in Figure 1, the web 36 forms a supporting shelf and guide member for the coupler shank outwardly of the carry iron member 20 of the railway draft rigging. Inwardly of the openings 29, the side walls 25 of the yoke means are provided with two additional aligned key receiving openings 38—38 for a purpose hereinafter more fully pointed out.
- An outer follower 39 is disposed within the yoke means immediately in back of the shoulders 30. The follower 39 has a rearwardly extending post 40 thereon which is in the form of a relatively heavy plate occupying the space between the side walls 25 of the yoke means. The post 40 is provided with a key receiving opening 41 extending lengthwise thereof and accommodating a transverse key 42 extending through the openings 38 of the side walls of the yoke means and having its opposite ends working in the slots 112—112 of the cheek plates.
- The key 42 is of the same type as the key 28, hereinbefore described. The opening 41 of the post is of such a length as to permit relative movement of the follower 39 and the key 42 to such an extent that the inner end of the post 40 will engage the end wall 27 of the yoke means and thereby limit the compression of the spring shock absorbing means.
- A pressure transmitting block 43 is interposed between the butt end of the coupler shank and the follower 39. As shown, the block 43 is provided with a cylindrical boss 44 rearwardly extending therefrom and seated in a cylindrical pocket in the front side of the follower 39. At the front side, the pressure transmitting block 43 is provided with a pocket 45 adapted to receive the butt end of the coupler shank. As shown in Figures 1 and 2 of the drawing, the top, bottom and side walls of the pocket 45 flare outwardly, but the inner end of the pocket is of such dimensions as to snugly fit the butt end of the coupler shank so as to prevent relative vertical displacement between the same and the block. As also shown in Figures 1 and 2 of the drawing, the top and bottom walls of the pocket are longer than the side walls, the side walls being cut away inwardly, as indicated at 46, to clear the coupler key 28. The block 43 is of such a height as to fit between the guideway formed by the wall portions 31 and 32 of the yoke means. As will be evident, the coupler shank is thus supported at the forward

end by the shelf 36 and is guided and supported at the rear end by the block 43 so as to prevent tilting or rocking of the coupler shank on the ledge 36.

A spring shock absorbing means, comprising a plurality of coils 47—47, is disposed within the yoke means, being interposed between the end wall 27 and the follower 39. As shown, the spring means comprises two upper and two lower coils disposed respectively above and below the post 40. 80

The inner end of the yoke means is supported by a saddle plate 48 secured to the lower flanges of the sills 10. As will be evident, the spring shock absorbing means and follower member disposed within the rear end of the yoke weights this end of the same, thereby overbalancing the coupler head and preventing rocking of the yoke on the carry iron 20. 90

A friction shock absorbing means comprising a friction shell 49 and a cooperating wedge 50 and friction shoes 51—51 is disposed between the inner end of the yoke and the abutment face 15 of the stop casting 14. The friction shock absorbing mechanism is of a well known design and needs no further detailed description; the same, 100 as will be understood, includes the usual spring resistance which is disposed within the shell 49 and opposes inward movement of the friction shoes. As is usual, retaining means in the form of a bolt is employed to limit the outward movement of the wedge of the friction shock absorbing means with respect to the shell. The wedge member 51 of the friction shock absorbing means directly engages the transverse end wall 27 of the yoke means and is actuated through the inward movement of the yoke during a buffering stroke of the coupler. In order to support the friction shell for longitudinal movement, a saddle plate 52 is employed which has the opposite ends secured to the bottom flanges of the sills 10. 115

The normal full release position of the parts of the mechanism is that shown in the drawings with the coupler head spaced from the front end of the yoke means, the key 42 in abutment with the front end walls of the openings 112, spaced from the inner end walls of the openings 112 and the openings 38 of the yoke means, and the front edge thereof spaced inwardly from the front end wall of the opening 41 in the post 40, and the inner end wall of the yoke spaced from the front end of the friction shell 49 and the stop shoulders of the arms 16. In this connection, it is pointed out that the friction shell is preferably of such a length as to have the front end thereof in alignment with the stop shoulders of the arms 16. The 120 coupler key 28 is in engagement with the front end walls of the openings 29 of the yoke means, but has the front edge thereof spaced from the front end walls of the openings 12 of the draft sills. It will thus be evident that the yoke means is pulled outwardly in unison with the coupler in draft. 125

The operation of my improved railway draft rigging during a buffering or inward movement of the coupler is as follows: The inward movement of the coupler will force the pressure-transmitting block 43 inwardly therewith, thereby forcing the follower 39 rearwardly toward the end wall 27 of the yoke means, inward movement of the 130 yoke means at this time being resisted by the friction shock absorbing mechanism. During the described inward movement of the coupler, the springs 47 will be compressed between the follower 39 and the end wall 27 of the yoke means, 135

the springs being preferably of lesser capacity than the friction shock absorbing mechanism.

There will, however, also be some compression of the friction shock absorbing mechanism during the compression of the springs 47 and the wedge block 50 will be forced rearwardly, carrying the friction shoes therewith along the friction surfaces of the shell and spreading the same apart due to the wedging action. Rearward movement of the follower 39 and compression of the springs 47 will be limited by engagement of the inner end of the post 40 with the transverse end wall 27 of the yoke means, whereupon the forces will be transmitted directly through the post to the end wall 27 and the friction shock absorbing mechanism until the latter is fully compressed and movement of the yoke is limited by engagement with the front end of the friction shell and the stop faces on the arms 16 of the stop casting. Upon the actuating force being reduced, the expansive action of the friction shock absorbing mechanism will return the yoke to the full release position shown in the drawings, outward movement of the wedge being limited by the usual retaining means of the friction shock absorbing mechanism. The other parts of the railway draft rigging will be restored to the normal position shown in Figure 1 by the expansive action of the springs 47, outward movement of the follower 39 being limited by the key 42 coming into engagement with the front end walls of the openings 112 of the draft sills. The coupler head is preferably spaced from the front end of the yoke means a distance equal to or very slightly greater than the clearance between the inner end of the post 40 and the wall 27 of the yoke, whereby the coupler head will closely approach the end of the yoke means when the spring shock absorbing mechanism is fully compressed.

Inasmuch as the coupler key 28 engages the front end walls of the openings 29 of the yoke, there will be no outward movement of the coupler with respect to the yoke during a draft action and the maximum spacing between the coupler head and the front end of the yoke means will never exceed the amount in full release as shown in the drawing.

During a draft action of the mechanism, the coupler will be pulled outwardly, carrying the yoke therewith through the medium of the key 28. The springs 47 will thus be compressed between the end wall 27 of the yoke and the follower 39, the latter being held stationary by the key 42, the rear edge of which is in engagement with the inner end wall of the opening 41 of the post and by engagement of the front edge thereof with the front end wall of the openings 112 of the draft sills. Compression of the springs will be limited by engagement of the end wall 27 of the yoke with the inner end of the post 40 and the forces will thereafter be transmitted directly to the draft sills preventing the springs from being unduly compressed. During the draft action, operation of the spring gear only will be effected, the friction shock absorbing mechanism remaining idle. The outward movement of the coupler and yoke is equal to the compression stroke of the spring shock absorbing means and the inward movement of the coupler is equal to the combined compression strokes of the spring shock absorbing means and the friction shock absorbing means. It will thus be evident that my improved railway draft rigging has a longer stroke in buff than in draft and that much greater

resistance is offered to the buffing stroke than to the draft stroke.

It is further pointed out that the ledge 36 which supports the coupler shank remote from the inner end thereof is at all times disposed outwardly of the carry iron, thus preventing pivotal movement of the coupler shank about the carry iron so as to maintain the coupler head in proper horizontal position and eliminate drooping of the same, the weight of the coupler head being overbalanced by the combined weight of the spring shock absorbing means, outer follower, pressure-transmitting block, and that portion of the yoke means disposed rearwardly of the carry iron 20. It will be understood that the inner end of the coupler shank is at all times held against vertical displacement by the pressure-transmitting block 43 which is guided between the wall portions 31 and 32 of the yoke.

While I have herein shown and described what I consider the preferred manner of carrying out my invention, the same is merely illustrative and I contemplate all changes and modifications which come within the scope of the claims appended hereto.

I claim:

1. In a draft rigging for railway cars, the combination with a coupler having a shank member; of a yoke movable rearwardly during a buffing action; a coupler key connecting the yoke and coupler; a front follower within the yoke, said follower having a rearwardly extending post thereon engageable with the inner end of the yoke to limit relative movement of the follower and yoke and effect movement in unison of said follower and yoke during buffing action of the mechanism, said post being longitudinally slotted; a key extending through the slot of the post and being movable lengthwise of said slot to an extent at least equal to the maximum relative movement of the follower and yoke, said key being held against outward movement with respect to the car and having movement inwardly of the car and yoke, said key limiting outward movement of the follower by engagement with the rear end wall of the slot of the post; and cushioning means between the follower and inner end of the yoke.

2. In a railway draft rigging, the combination with draft sills having transversely aligned key slots; of a coupler having a shank member; a yoke connected to the coupler for movement therewith in draft; front follower means within the yoke, said front follower means having a rearward extension, said extension being provided with a longitudinal slot; a stop key extending through the slot of said extension and having movement in said slot lengthwise of said extension, said key having its forward movement limited by engagement with the front walls of said sill slots and having shouldered engagement with the rear end wall of said follower slot for limiting outward movement of the follower means, said extension on said follower means being of a length to engage with the inner end of the yoke for limiting inward movement of the follower means with respect to the yoke and move said yoke rearwardly with said follower means after a predetermined relative movement of said follower means and yoke while said key is held against rearward movement by engagement with the rear walls of said sill slots; and cushioning means interposed between the inner end of the yoke and said follower means.
